MECHANICAL PENCIL

Lucifer J. Most, Hudson County, N. J.

Application September 30, 1939, Serial No. 297,241

5 Claims. (Cl. 120—18)

My invention relates to mechanical pencils of the type in which the lead is an instrumentality of the pencil mechanism.

The object of the invention is to provide leads that will interlock in the means for feeding the lead and thereby provide a continuity of feed.

In my allowed application Serial No. 279,072, filed June 14, 1939, allowed July 21, 1939, I have disclosed a pencil with prismatic leads which is 10 the shape most suitable for leads whose average diameter in cross-sectional area is less than $\frac{1}{8}$ th of an inch. For leads having in cross-section diameters larger than $\frac{1}{8}$ th of an inch the shape may be either cylindrical or oval, and therefore 15 not necessarily prismatic, as the guides in such larger diameters can be easily made to suit the cross-section of the larger diameter of either oval or circular shaped leads in cross-section.

In the appended drawing forming part of this 20 application, Figure 1 is a fragmentary vertical section on line 1—1, Figure 2, showing a pencil embodying my invention.

Figure 2 is an enlarged cross-section on line 2—2, Figure 1.

Figure 3 is an enlarged cross-section of a pencil having an oval shaped lead guide, and therefore, oval shaped lead in cross-section, and

Figure 4 is a perspective view of a lead oval in cross-section.

Referring to the drawing, 5 is a barrel which is provided with a customary tip 6 terminating at the lead outlet with a threaded bore 7. Positioned within the barrel and revolving relatively thereto is a magazine 8 having a lead guide 9 of circular cross-section extending through the bore 10 of the tip and leading to the threaded bore 7.

The magazine is provided with an outer bead 11 bearing against a ring 12 secured within the barrel, and with the bearing of the end of the 40 lead guide 9 on the bottom of the bore 10, the magazine is prevented from longitudinal displacement in the barrel. The magazine carries an eraser 13 and a cap 14 by which the magazine may be turned in the barrel. The leads 15 for the pencil in this particular case are cylindrical and are circular in cross-section similar to the lead guide 9. To prevent the lead from 45 turning in the guide the lead is provided with a keyway 16 which is engaged by protuberances 17 formed in the guide preferably near the ends thereof.

Each of the leads has its ends cut on a bias, that is to say, forming slopes 18 which are at an angle with the axis of the lead. When a lead is 50 fed through the threaded bore 7 of the tip by the

turning of the magazine, the upper end of slope 18 of a lead 15 passes from the magazine into the guide 9 when another lead 15 will enter into the guide 9 following the lead which is already in the guide. If the two slopes 18 of the contacting leads do not meet properly at the time, they will travel that way toward the threaded bore 7 until the lower lead 15 passes substantially into the threaded bore 7 when it will remain stationary, while the lead above it will be turned by the 10 guide 9 which turns with the magazine. This brings the slope 18 thereof in register with the upper slope 18 of the lower lead 15 positioned in the threaded bore 7 of the tip, as shown in Figure 1. In consequence of this engagement, the 15 lower portion of the lead 15 will turn when the upper lead 15 above it is turned by the magazine through the guide 9. This engagement of the contacting slopes of the leads insures the expulsion of the lead section engaged in the threaded 20 bore 7.

In Figure 3, the lead barrel 5' has the lead magazine 8' provided with a lead guide 9' which is circular exteriorly but oval interiorly, that is, the passage 10' of the lead guide is oval in 25 cross-section to engage a lead 15' of similar cross-section. In this arrangement no keyways in the lead proper are necessary since the lead will not turn in the lead guide, although it is free to move longitudinally due to its shape.

Figure 4 illustrates in perspective a lead as 30 shown in the cross-section of Figure 3.

In lieu of forming a keyway, as shown in the leads of Figures 1 and 2, a flat surface in lieu thereof could be provided which will answer the same purpose. It is self-evident that the lead guide will have corresponding flat surfaces to engage the lead and prevent it from turning while permitting it to move longitudinally thereof.

The fact that the lower lead when entirely in 40 the threaded bore 7 remains stationary but the lead above it will turn until the two slopes meet, does not necessitate an exact cutting of the slope or relatively to the configuration of the lead used.

Although the description and drawing refer to a threaded tip mechanism, it is obvious that a threaded member for the lead may be located at any other portion in the barrel or tip using the lead described, that is, a lead having the ends 45 cut on a bias.

I claim:

1. In a mechanical pencil, a lead, means for feeding the lead, and means for preventing the 50

lead from turning while permitting the lead to move longitudinally thereof, said leads having its ends cut on a bias.

2. A lead for a mechanical pencil having its ends cut on a bias.

3. In a mechanical pencil, a combination of a lead having its ends cut on a bias, and a guide

for lead which permits said lead to move longitudinally but prevents it from turning therein.

4. A lead for mechanical pencil having sloping ends.

5. A lead for mechanical pencil having sloping ends lying in substantially parallel planes.
